CLAIM

The ornamental design for a detachable sighting mirror for golf putters, as shown and described.

DESCRIPTION

FIG. 1 is a perspective view of a detachable sighting mirror for golf putters showing my new design;

FIG. 2 is a top plan view thereof;

FIG. 3 is a left side elevation thereof;

FIG. 4 is a front elevation thereof;

FIG. 5 is a rear elevation thereof; and,

FIG. 6 is a bottom plan view.

The right side elevation is a mirror image of the side shown.
